UNITED STATES PATENT OFFICE.

ELMER JOHN MAYER, OF NEW YORK, N. Y., ASSIGNOR TO JOSEPH SCHNEPS, OF NEW YORK, N. Y.

AMUSEMENT DEVICE.

1,420,437.

Specification of Letters Patent. Patented June 20, 1922.

Application filed November 16, 1920. Serial No. 424,428.

To all whom it may concern:

Be it known that I, ELMER J. MAYER, a citizen of the United States, and a resident of the city of New York, borough of Manhattan, in the county and State of New York, have invented a new and Improved Amusement Device, of which the following is a full, clear, and exact description.

The present invention relates to new and useful improvements in amusement devices, and it pertains more particularly to devices of this character of the carrousel type.

It is one of the primary objects of the invention to construct a device of this character in such a manner that a plurality of passenger carrying elements, such as cars, are carried around a circular track, the surface of which is of an undulated character.

It is a further object of the invention to so construct a device of this character that the passenger-carrying elements above mentioned will have pivotal movement in both the direction of and the direction opposite to the circular direction of travel.

It is a further object of the invention to so construct these passenger-carrying elements as to provide for vertical movement thereof as the same travel over the undulations of the track.

With the above and other objects in view, reference is had to the accompanying drawings in which—

Figure 1 is a top plan view of a device constructed in accordance with the present invention;

Fig. 2 is a side elevation thereof;

Fig. 3 is a detail view partly in elevation and partly in section;

Fig. 4 is an enlarged detail perspective view of a portion of the device;

Fig. 5 is a detail top plan of a modified form of the invention;

Fig. 6 is a detail sectional view showing the method of mounting the cars in the modified form of the invention;

Fig. 7 is a similar view taken at right angles to Fig. 6.

Referring more particularly to the drawings, the device comprises a circular track 10, and as more clearly shown in Fig. 2, the surface of said circular track is of undulated character and constructed with raised por-

tions 11 and depressed portions 12, which form hills and vales over which the several passenger-carrying elements are to be moved in a manner to be hereinafter more specifically pointed out.

The circular track 10 is preferably formed by vertical standards 13 arranged in spaced relation to each other and connected by cross beams 14 upon which the tread surface 15 of the track is laid. In order to brace the vertical standards 13, circumferential members 16 and 17 are employed upon the exterior and interior edges of the track, respectively, and upon the interior edge of the track a runner 18 is provided, said runner projecting slightly above the track as indicated by the reference character 19.

Mounted centrally of the track is a base 20 or the like 20, and mounted upon the upper face of said base 20, is a bearing member 21. Pivotally mounted upon this bearing member 21, by means of a bolt 22', is a bearing plate 22, and interposed between the bearing member 21, and the bearing plate 22, are anti-friction elements 23. This bearing plate 22 is preferably circular in form and is provided around its edge with spaced flanges 24, which flanges are perforated for the reception of bolts 25.

Mounted interiorly of the track in circular relation one to the other, is a plurality of foundation blocks 30, and each of these foundation blocks 30 carries upon its upper face, spaced trunnions 31, the upper end of each of which is provided with a bearing 32. Mounted in the bearings 32 on each of these devices, is a shaft 33, and suitably carried by said shaft 33, is a roller 34. It is to be understood that these blocks 30 together with the mechanism described, are positioned at various points throughout the inner circumference of the track 10, there being sufficient number to properly support and prevent sagging of the circular ring member 35. This ring member 35 comprises two concentric members 36 and 37 superimposed with relation to each other, and these members 36 and 37 are preferably channel-shaped in cross-sectional form as more clearly shown in Fig. 3. These members 36 and 37 are secured together by rivets or the like 38, which pass through the meeting flanges of the two

members. The lower member 37 is adapted to rest upon the rollers 34, while the upper member 36 is adapted to carry the means by which the passenger-carrying elements are 5 secured to the ring.

Connected to the bearing plate 22 by the bolts 25 heretofore mentioned, is a plurality of rods 39, and rigidly connected to the base portion of the channel which forms the upper 10 per ring 36, as at 40, is a plurality of rods 41, each of which is in axial alinement with one of the rods 39.

To secure the two members 36 and 37 together in order that the circular member 35 15 may at all times maintain its concentric relation with the track, supporting rollers 34, and the central bearing member, an internally screw-threaded sleeve 42 is provided, which receives the adjacent ends of the rods 20 39 and 41, said ends being screw-threaded as 25 indicated by the reference character 43.

As more clearly shown in Fig. 1, the top member 36 is provided at equidistantly spaced points with a pair of spaced plates, 50 and 25 said plates are secured to the top member 36 above that point where each of the rods 41 is connected thereto. To give additional support to the spaced plates 50, an angle iron 30 51 is secured to the rear face or base of the channel which forms the member 36, as more clearly shown in Fig. 3, said spaced plates 50 being secured to the member 36 and the angle iron 51 by means of rivets 52 and 53, respectively. These spaced plates 35 50 are adapted to form the means by which a plurality of cars are pivotally secured at equidistantly spaced points about its circumference, to the top member 36.

The reference character 55 designates the 40 cars, and interposed between each of the cars 55 and the ring member 35, is a triangular frame 56, the apex of which is positioned outwardly of the track and is provided with a socket 57 in which is seated a 45 pole 58 carried by an extension 59 on the forward end of each of the cars. Each of the legs of the triangular member 56 is pivotally mounted, by means of a bolt 60, between a pair of plates 50 in order that these 50 triangular members 56 may have a vertical movement between the plates 50 and relative to the ring 35 and the track 10. To support the outer end of each of the triangular members 56, they are provided at that point beneath their connection with the extensions 55 of the cars 55, with castor wheels 61. Each of the cars is substantially triangular in top plan view, and said cars are provided on their rear ends, with castor wheels 63 and 60 upon opposite sides adjacent their rear ends they are provided with spring buffers or the like 64.

In Figs. 1 and 2 of the drawings, is shown means by which the device is driven, said 65 means comprising an electric motor 65, suit-

ably mounted beneath the track 10, and said motor 65 drives a pulley 66, by means of a belt 67. The pulley 66 is mounted on a shaft 68 carried by bearings 69 and mounted on the shaft 68, is a second pulley 70. Passing around this pulley 70, is a cable 71, and said cable 71 is adapted to lie within the lower circular member 37 as shown in Fig. 3. By this construction, it will be apparent that as the motor 65 drives the shaft 68, the 75 pulley 70 will be driven and through the medium of the cable 71, the circular member 35 will be rotated. As the circular member 35 is rotated, it will be seen that the cars 55 will be carried around the circular track 10, and that as the cars approach one of the inclined or raised portions 11, they will assume a position at right angles to their respective triangular member and the longitudinal axis of each car will be substantially parallel to the direction of travel. When, however, the apex of each raised portion is reached, the car is advanced down the declined portion to the next lower portion 12, and the rate of speed of this travel will 80 be greater than the rate of speed of travel of the circular member 35.

By this construction, it will be seen that the several cars would be advanced with an intermittent motion since they would pause 95 within the depressions of the track 10 a sufficient length of time to permit the circular member 35 to reach its position relative to the track 10, during which period the cars would be subjected to a slight jerky 100 motion on the surface of the track without traveling therealong.

In the form of the invention shown in Figs. 5 to 7, inclusive, the cars 55 are each carried by a rigid beam 100, and said rigid beams are pivoted between flanges 101 carried by plates 102 mounted upon the circular member 35. The means by which these rigid beams 100 are pivotally secured, consists of a universal joint 103, having a horizontal pivotal point 104 and a vertical pivotal point 105. In this form of the invention, a rod 110 is pivotally secured, as at 111, to each side of each of the beams 103, and pivotally secured as at 112, to the circular member 35, are rods 113. These rods 113 are arranged in axial alinement with their respective rods 110, and when in this position, a spring 114 is passed around the rods to provide shock-absorbing means for 115 the cars 55.

In this embodiment of the invention, it will be seen that the cars will normally be carried in a position which is substantially at right angles to the axis of the circle, and will only vary slightly from this position as the compression of the springs 114 will 125 permit.

From the foregoing it will be apparent that the present invention provides a new 130

and improved amusement device in which in addition to a circular direction of travel, the passenger-carrying elements of the device are subjected to jerky, intermittent motions which greatly add to the novelty of the device.

In addition to the foregoing, a vertical or up-and-down movement is provided, which also lends to the attractiveness of a device of this character.

I claim:

1. In an amusement device, a stationary circular track, a circular member mounted interior of the track and concentric therewith, means for driving said interior member, a plurality of triangular frames pivotally mounted upon said interior circular member, and a passenger-carrying car pivotally mounted upon the outer end of each of said triangular frames.

2. In an amusement device, a circular track, a circular member mounted interior of the track and concentric therewith, means for driving the interior circular member, a plurality of triangular frames pivotally carried by the circular member, a castor wheel for supporting one end of each of said triangular frames, said castor wheels being movable over the track, and a plurality of passenger-carrying cars adapted for movement over the track, each of said cars being

pivotsally connected to one of the triangular frames at a point directly over its castor wheel.

3. In an amusement device, a circular track having an undulated tread surface, a circular member mounted interior of the track, means interior of the track for supporting said circular member and permitting of a rotary movement thereof, means for driving the interior circular member, a plurality of triangular frames pivotally connected to the circular member and extending over the track, a castor wheel for supporting that end of each of said frames which projects over the track, and a passenger-carrying car pivotally pivoted to the outer end of each of said frames at a point above the castor wheel thereof.

4. An amusement device comprising a circular track having an undulating surface, a circular member mounted within said track, means for driving said circular member within the track, means pivotally connected to the inner circular member and overlying a portion of the track, and a plurality of passenger-carrying cars, said cars being pivotally connected to the inner circular member by the means pivoted thereto and extending over a portion of the track, substantially as described.

ELMER JOHN MAYER.
